UNITED STATES PATENT OFFICE.

JAMES H. WHITE, OF ELECTRA, CALIFORNIA.

GARMENT-FASTENER.

No. 847,217.

Specification of Letters Patent.

Patented March 12, 1907.

Application filed January 3, 1906. Serial No. 294,361.

To all whom it may concern:

Be it known that I, JAMES H. WHITE, a citizen of the United States, and a resident of Electra, in the county of Amador and State of California, have invented a new and Improved Garment-Fastener, of which the following is a full, clear, and exact description.

The invention relates to a fastener intended for joining the parts of garments and other fabrics. It is particularly useful as a skirt-fastener, in which connection I have chosen to illustrate it here.

The object of the invention is to provide a fastener the parts of which may be engaged with each other by a very slight movement, and which when engaged will hold securely.

A further object is to so construct the fastener that it will lie flat against the wearer and present a smooth neat appearance, particularly when it is used in connection with a skirt.

Various other objects are contemplated, all of which with the peculiar construction involved will be fully set forth hereinafter and the novel features particularly pointed out in the claims.

Reference is to be had to the accompanying drawings, which illustrate as an example the preferred embodiment of my invention, in which drawings—

Figure 1 is a fragmentary rear view showing the parts of a skirt fitted with my fastener. Fig. 2 is a section on the line 2 2 of Fig. 1. Fig. 3 is a detail sectional view of one part of the fastener on the line 3 3 of Fig. 2; and Fig. 4 is a cross-section with two fastener-sections engaged together, the section being on the line 4 4 of Figs. 1 and 2.

In order to fit the fastener for effective use in connection with a skirt and to make the fastener lie flat and concealed as fully as possible, I provide the sections A and B with offsets 10 and 11, respectively, which receive the heavy binding or filling fabric 12 at the inner side of the skirt. 14 indicates the facing or outer fabric of the skirt, and this extends through the outer side of the section A to the shoulder 15, forming the offset portion 10, so that the fabric 14, stitched to said offset portion 10, is turned around the shoulder, as shown in Fig. 2. The fabric 14 passes completely over the outer side of the section B and is turned around the curved edge 16 thereof, to which edge it is stitched or otherwise secured. Fig. 3 shows said curved edge

16 provided with openings through which the thread may be passed for holding the fabric 14 to said section B. The heavy filling fabric 12 of the skirt lying inside of the facing 14 extends into the said offset portions 10 and 11 of the sections A and B, as before described, and its edges are arranged to abut against the shoulder 15 of the offset 10 and a similar shoulder 17 of the offset 11. All of the parts are provided with orifices which facilitate stitching the fabric thereto.

The sections of the fastener are formed of sheet metal and are preferably stamped to the desired form. The section A is formed with a triangular or wedge shaped outwardly-bulged portion or projection 18, the converging sides of which overhang so that they may lock with the correspondingly-disposed walls 19, formed on the section B. Said walls 19 may be formed in any desired manner. In Fig. 4 they are illustrated as struck or stamped up from the metal of which the section B is composed. The walls 19 converge toward each other and are arranged to overhang the surface of the section, as shown in Fig. 4, so that they will lock with the converging sides of the projection 18. By means of these devices the sections of the fastener are held together. It will be seen that by very slight relative movement the sections may be engaged and locked with each other. In order to hold the parts against accidental disconnection, the projection 18 is formed with a cavity 20, and this is adapted to be engaged by a protruded portion 21 on a spring-tongue 22, which tongue is formed integral with the sheet metal of the section B, so that when the sections are engaged the protuberance 21 springs into the cavity 20, thus holding the parts against accidental disconnection. At the same time by the application of a positive pressure the spring-tongue 22 may be readily overcome and the fastener-sections engaged or disengaged, as described.

It will be seen that by means of my device a very neat and secure fastening is provided and one which is especially adapted for application to women's skirts, the fastener holding the parts of the skirt firmly together and lying flat against the wearer, so that the waistband of the skirt presents a smooth and practically unbroken appearance. This is illustrated in Fig. 2, where the two edges of the facing fabric 14 are shown to abut snugly together. The fastener is not, however, lim-

ited to use in skirts. It may be applied to garments and various other fabric articles with equal facility.

In operation the projection 18 of the section A is engaged in the walls of the section B, the shoulder 15 being slipped in front and beyond the shoulder 16 slightly to facilitate the introduction of the projection. When the shoulder 15 is placed in its normal position, so that the offset portion of the section A is in alignment with the main portion of the section B, the sides of the projection 18 are forced into firm contact with the walls 19 of the plate B and the projection on the spring-tongue 22 engages with the recess 20. In unfastening the fastener the shoulder 15 is pushed forward out of engagement with the shoulder 16 and moved thereover, thereby bringing the projection 18 out of engagement with the walls 19. The tongue 22 being resilient permits the projection 21 to move out of the recess 20 when slight force is exerted in the separation of the sections.

Having thus described the preferred form 25 of my invention, what I claim as new, and desire to secure by Letters Patent, is—

1. A garment-fastener comprising two sections each of which is formed with an offset portion, a shoulder joining the offset portion

to the main part of the section, the said offset portion serving to receive parts of the garment, one section of the fastener having a wedge-shaped or essentially triangular projection with overhanging side walls, and the other section having converging overhanging walls respectively adapted to engage and lock with the side walls of the said projection, and a spring-tongue carried on the second section and adapted resiliently to engage the other section, for the purpose specified. 30

2. A garment-fastener comprising a plurality of sections, having oppositely-offset portions for attachment to the garment, one of said sections having a substantially triangular projection with its base adjacent to the 45 edge of the section, the sides of the projection overhanging the section, and the other section having walls for receiving the projection, and resilient means in connection with the sections for retaining them in position. 50

In testimony whereof I have signed my name to this specification in the presence of two subscribing witnesses.

JAMES H. WHITE.
